UNITED STATES PATENT OFFICE.

WILLIAM N. MORRISS, OF WATERLOO, IOWA.

FIRE EXTINGUISHER.

Application filed November 12, 1921. Serial No. 514,734.

To all whom it may concern:

Be it known that I, WILLIAM N. MORRISS, a subject of the King of Great Britain, and a citizen of Australia, residing at Waterloo, in the county of Blackhawk and State of Iowa, have invented certain new and useful Improvements in Fire Extinguishers, of which the following is a specification.

This invention relates to fire extinguishers, and has for its object the production of a simple and efficient extinguisher, which will explode when thrown into a fire, or when the same is ignited, thereby spreading the extinguishing chemical over a wide area.

Another object of this invention is the production of a simple and efficient means for containing extinguishing chemical in such a manner as to cause the chemical to be automatically spread over a fire, when brought in contact with fire.

Other objects and advantages of the invention will appear throughout the following specification and claim.

In the drawings:

The figure is a vertical sectional view through the fire extinguisher.

By referring to the drawings, it will be seen that 1 designates the casing, which is provided with an open bottom and a tapering top 2. The casing 1 is preferably made of strong paper chemically treated to insure against dampness affecting the contents of the casing, and also for reinforcing the extinguisher. It should be understood, of course, that the casing may be made of any suitable material, without departing from the spirit of the invention. A metal cap 3 fits over the bottom of the casing 1 and is secured thereto, the same constituting a closure for the casing and also strengthening the lower end thereof. A metal handle 4 is secured to the lower end of the cap 3 to facilitate the carrying of the extinguisher. The handle 4 may be hung over a suitable support, such as a hook, for supporting the device in a convenient place.

A cartridge 5, containing explosive chemicals 6, is fitted in the center of the container or container casing 1, and carries a fuse 7, having diverging ends 8. The upper end of

the fuse 7 extends through the protector tube 9, which tube extends centrally of the tapering end 2 of the casing 1, and protects the fuse from the extinguishing chemicals 10, which are mounted or packed in the container 1 around the cartridge 5. The fuse 7 extends beyond the tapering end 2 of the casing 1 and may be either lighted before being thrown on the fire, or may be lighted by the fire, in which the same is thrown.

From the foregoing description, it will be seen that a very efficient means has been produced for facilitating the spreading of fire extinguishing chemical over a wide area, through the explosion of a cartridge mounted in a container carrying a fire extinguishing chemical. It is not desired to limit the present invention to any particular chemical used therewith, and it should be understood that certain detail mechanical changes may be employed without departing from the spirit of the invention, so long as these changes fall within the following specification and claim.

What is claimed is:

As a new article of manufacture, a fire extinguisher comprising an exterior casing formed of stiff paper treated to resist dampness including a cylindrical side wall and a conical closure extension formed on the forward end of the side wall, a rigid metal cap secured to the rear end of the side wall acting as a closure for the casing, a handle secured to said rigid metal cap, an axially disposed longitudinally arranged cartridge positioned in the casing in spaced relation to the side wall, the conical extension and the metal cap, a protecting tube extending forwardly from the cartridge to the vertex of the conical extension, and a fuse disposed in the tube and communicating with the cartridge and extending exteriorly of the casing at the vertex portion of said conical extension.

In testimony whereof I affix my signature in presence of two witnesses.

WILLIAM N. MORRISS.
